(57) **CLAIM**

The ornamental design for an electronic sign, as shown and described.

DESCRIPTION

FIG. 1 is a perspective horizontal view of the electronic sign; FIG. 2 is a perspective horizontal view of the opposite side of the electronic sign;

FIG. 3 is a horizontal front view of the electronic sign;

FIG. 4 is a horizontal rear view of the electronic sign;

FIG. 5 is a horizontal side elevation view of the electronic sign;

FIG. 6 is a horizontal top side view of the electronic sign;

FIG. 7 is a horizontal bottom side view of the electronic sign.

FIG. 8 is a perspective horizontal view of an alternate embodiment of the electronic sign with reversed positions of the windows;

FIG. 9 is a perspective horizontal view of the opposite side of FIG. 8;

FIG. 10 is a perspective front view of the electronic sign of FIG. 8;

FIG. 11 is a horizontal rear view of FIG. 10;

FIG. 12 is a horizontal side elevation view of the electronic sign;

FIG. 13 is a horizontal top view of the electronic sign; and,

FIG. 14 is a horizontal bottom side view of the electronic sign. The broken lines in the drawings depict environmental subject matter only and form no part of the claimed design.

1 Claim, 6 Drawing Sheets
